DISPLAY CONTAINER

Walter J. Tyrseck, Montville, Conn., assignor to
 Robertson Paper Box Co., Inc., Montville,
 Conn., a corporation of Connecticut

Application December 3, 1948, Serial No. 63,329

6 Claims. (Cl. 229—28)

1

This invention relates to improvements in display containers.

More particularly, the invention is concerned with providing a container for display, and preferably also for shipment, of a number of articles, the container comprising built-in partitions for forming sub-compartments and being capable of construction as a single blank which may be manufactured on the continuous roll-around principle by present automatic machinery and shipped to the customer in collapsed condition.

For a full understanding of the invention, a detailed description of the container will now be given in connection with the accompanying drawing and the features forming the invention will then be specifically pointed out in the appended claims.

In the drawing:

Figure 1 is a flat view of a container blank;

Figure 2 is a view showing the container in the collapsed condition in which shipped to the customer;

Figure 3 is a plan view of the container after setting up;

Figure 4 is a section on the line 4—4 of Figure 3;

Figure 5 is an end elevation view of the set up container of Figures 3 and 4;

Figure 6 is an isometric view showing also in phantom the outline of a suitable outer carton for use in shipping the goods;

Figure 7 is a flat view of another container blank adapted for forming a carrier for soft drink bottles or the like;

Figure 8 shows a carrier formed from the blank of Figure 7 in collapsed condition;

Figure 9 is a side elevation of the carrier of Figure 8, in set up condition and partly broken away to show the internal structure;

Figures 10, 11 and 12 are, respectively, plan, elevation and isometric views of the carrier of Figure 9;

Figure 13 is a flat view of still another container blank adapted for forming a partitioned box;

Figure 14 shows a collapsed container formed from the blank of Figure 13;

Figure 15 is a side elevation view partly broken away, showing the container of Figure 14 in set up condition;

Figure 16 is a section on the line 16—16 of Figure 15;

Figure 17 is a plan view of the container of Figure 15;

Figure 18 is a flat view of a blank adapted for

2

forming a container having twelve sub-compartments;

Figure 19 shows the collapsed container which is formed from the blank of Figure 18;

Figures 20 and 21 are, respectively, side and end elevation views of the set up container formed from this blank, certain parts being broken away to show internal structure;

Figure 22 is a plan view of the container of Figure 20;

Figure 23 is an isometric view of the container of Figure 20 with parts broken away to show the internal structure;

Figure 24 is a plan view of a blank for forming still another type of container;

Figure 25 shows this container in collapsed condition;

Figure 26 is a front elevation view, with parts broken away, of the container of Figure 25 in set up condition;

Figures 27 and 28 are sections on the lines 27 and 28, respectively, of Figure 26;

Figure 29 shows still another blank for forming a container having partitions for forming a spacer therein;

Figure 30 shows a container formed from the blank of Figure 29, in collapsed condition;

Figure 31 is a plan view of the container of Figure 30, in set up condition; and

Figures 32 and 33 are, respectively, front and bottom elevation views of the container of Figure 31.

In the embodiment shown in Figures 1 to 6, the display container proper is open at the top as shown in Figures 3 to 6, inclusive, and contains six sub-compartments for holding a number of packages or articles. The container will normally be formed of paper, pasteboard or similar material which lends itself to manufacturing processes usual in the paper box industry, typified by printing, die cutting, creasing and glueing and folding.

The blank, as shown in Figure 1, comprises panels 2, 4, 6, 8, 10, 12 and 14, as defined by the blank boundaries, longitudinal score lines 3, 5, 7, 9, 11 and 13 and transverse score lines 15, 17, 19 and 21. Score lines are indicated by dotted lines and cuts by solid lines. The score lines 3 and 5 may include short cuts, as indicated, to facilitate a sharp bend. Slots 23 and 25 are formed in panel 4 for accommodating partition flaps later described.

Cutouts 24 and 26 are made in the panels 8, 10 and 12. The purpose of the cutouts is to furnish a view of articles held within the container,

and from a structural standpoint they may be neglected.

Bottom flaps 28 and 30 continue the respective panels 8 and 12, being separated therefrom by the score lines 21 and 17. The flap 28 has a pair of cuts 29 and 31, as shown, and the panel 30 has an extension 32, separated therefrom by score line 33 and cut 35, and formed with a projection 31. The elements just described serve for holding the bottom together in the manner described below.

The panel 10 has a flap extending therefrom and separated from it by the score line 19, the flap comprising an intermediate section 36 and terminal section 38 defined by the boundaries of the blank and score line 39. A small slot or notch 40 is formed on the terminal flap section 38 for cooperation with the slot 23 previously referred to. The panel 14 is similarly continued by a flap having sections 42 and 44 separated by a score line 43 and a deeper notch or slot 46 is formed on the terminal section 44 for cooperation with the slot 25 of panel 4.

The blank as thus described is adapted for folding in high speed automatic machinery of existing design by continuous folding or rolling over in a single direction and in folding will pass through such a machine in parallelism to the longitudinal score lines 3, 5, 7 etc. The terminal panel 2 is not a panel in the sense of forming a wall or partition of the box but is a flap or tab for attaching panels together as later described.

The upper surface of the blank as shown in Figure 1 will be arbitrarily referred to as the "face" of the blank and the opposite side as the "reverse" of the blank for convenience and definiteness in description.

The first fold occurs on the score line 5, turning the flap 2 and panel 4 over onto the panels 6 and 8 in face to face relation thereto.

The second fold occurs on the score line 9, turning the entire structure to the right of this score line over, so that it lies upon the blank to the left of the score line. As will be apparent, part of the face of the panel 8 overlies panel 10 and the reverse of panels 2 and 4 overlies panels 10 and 12. The terminal panel or flap 2 had previously been prepared with adhesive on its reverse over an area C, indicated in phantom in the drawing, and will thus be joined to panel 10.

The third and last fold, forming the collapsed container, occurs on the line 13, panel 14 being folded over so that it lies partly over the face of panel 12 and covers the reverse of panel 6. Panel 6 will previously have been prepared with adhesive on its reverse over the area B, indicated in phantom in the drawing, and will thus be joined to the panel 14.

While the last fold occurs from left to right instead of the reverse as it is more convenient from the manufacturing standpoint to fold over the single panel 14 rather than the entire folded structure to the right thereof, it will be apparent that the effect of this so far as the blank is concerned is the same as though the last fold had been made so as to place the structure to the right of score line 13 over the panel 14 so that the folding is in actuality continuously in one direction so far as the blank is concerned.

The collapsed container thus produced is shown in Figure 2 in which the suffix "F" is applied to a reference numeral to indicate that the visible surface of the panel is the face thereof and the suffix "R" is used to indicate that the visible surface of the panel is the reverse thereof. The con-

tainer is shipped to the customer in the collapsed condition of Figure 2 and is set up prior to filling it with the articles to be shipped and displayed, as is usual with collapsible paper boxes. Forcing the edges of the collapsed container together by applying pressure against fold lines 9 and 13 will open the container out into a generally rectangular form, panels 10 and 14 being parallel, panels 8 and 12 being parallel and panel 4 extending as a partition down the middle and in parallelism to the last mentioned pair of panels. The flaps 42-44 and the flap 36-38 are now folded inwardly and upwardly on the score lines 15, 19, 39 and 43, wiping the terminal flap sections 38 and 44 into the slots 23 and 25 of the center partition panel 4. This is a rapid and easy setting up operation since the notches or slots 40 and 46 serve as guides and are positioned in alignment with the slots 23 and 25 with no difficulty whatsoever. Flap sections 36 and 42 now extend at right angles to the end walls 10 and 14 and terminal flap sections 38 and 44 are parallel to these end walls forming transverse partitions which in cooperation with the longitudinal partition 4 divide the box into six compartments, as indicated in Figures 3 and following. Flap 28 is now folded over on score line 21 and flap 30 is folded over on score line 17, the projection formed by cutout 35 is tucked into the cut 29 and the projection 31 is tucked into the cut 31, thus securely holding the bottom structure of the box together. The completed box structure is clearly shown in Figures 3, 4 and 5 and requires no further description.

Each of the six compartments of the completed container may be used for holding articles to be shipped, displayed and sold. In Figure 6, four such articles A are shown as occupying one of the compartments and it will be understood that the remaining five compartments will be similarly filled. Visibility is provided by the cutouts 24 and 26, as clearly appears from Figure 6. For shipment of the goods, the package will be completed by an outer carton as indicated in phantom at 50 in Figure 6, this carton being slid down over the container and its flaps being folded over the bottom thereof.

First modification

Similar principles of construction may be employed to make a carrier for a half-dozen soft drink bottles, of a generally familiar type. The blank for such a carrier and the carrier formed therefrom are illustrated in Figures 7 to 12. In those figures, elements similar to those shown in Figures 1 to 6 are identified by similar reference numerals, but increased by 100, so that the construction and manner of folding will be clear immediately with a minimum of further description.

In the carrier of Figures 7 to 12, the center partition panel 104 (which corresponds generally to the panel 4 of Figures 1 to 6) is formed with a cutout to make a handle and has a matching element 104a separated from it by a score line as shown in Figure 7. The element 104a is folded over on the panel 104, thus reinforcing it and this folding may be done at any convenient stage, either before shipment of the collapsed blank, as indicated in Figure 8, or afterwards. The bottom closure is modified somewhat, a tab 129 on panel 108 being inserted into a slot 135 at the edge of the bottom 130 and flap 132 being tucked up inside the carrier. The parts may be fastened by adhesive or staples, or by both, as convenient.

Adhesive prepared areas B and C are indicated on the reverse of the blank. The adhesive B on the reverse of panel 106 may be replaced with adhesive on the face of the corresponding contacting surface of the front of panel 114.

Second modification

Figures 13 to 17 illustrate a further modification in which a compartmented box with a flap closure for the top is constructed. In these figures corresponding elements are identified by the same reference numerals as used in Figures 1 to 6, but increased by 200, so that but little further description is required.

It will be noted that flaps 210a, 214a and 208a-208b are provided on the upper edge of the blank, making a tuck-in top. It will also be noted that panel 28 of Figure 1 has been eliminated and that flap 230-232 forms a tuck-in bottom of familiar type, the portion 230 extending clear across the box and eliminating need for an element corresponding to the panel 28 of Figure 1.

Third modification

Still another modified form of container is illustrated in Figures 18 to 23, and in this form twelve compartments or subdivisions are provided. Successive panel elements 252, 254, 256, 258, 260, 262 and 264 are provided, these being separated by longitudinal score lines 253, 255, 257, 259, 261 and 263. A terminal flap 250, foldable on score line 251 is also provided. These elements form the end walls, side walls and a partition wall for the container, the remaining elements being transversely foldable and forming the top, bottom and remaining partition walls in the manner described below. The folding operation for forming the collapsed container, as shown in Figure 19, is similar to that already described with reference to Figures 1 to 6, and is performed in the following way. The first fold occurs on line 261 bringing panels 262 and 264 in face to face relationship with panels 260 and 258. The second fold occurs on line 257 bringing the reverse of panels 262 and 264 over panels 256 and 254. The terminal panel or flap 264 will previously have been prepared with adhesive on its reverse side over the area B, indicated in phantom outline, and will thus be joined to panel 256. The last fold occurs on line 253 bringing the structure to the right thereof over on to the folded elements so that the face of terminal panel or flap 250 overlies the reverse of panel 258. Panel 250 will previously have been prepared with adhesive, as indicated at C, and will thus be joined to panel 258. The collapsed container thus produced is shown in Figure 19, and comprises a rectangular sleeve having a partition 262 for dividing it into compartments, one of which is of one-third the width of the other.

Elements 266, 268, 270 and 272, which are foldable on the score lines 267, 269, 271 and 273 form a top closure. When the collapsed container of Figure 19 is opened out, the end flaps 268 and 272 may be folded over and the side flaps 266 and 270 are then folded over. Flap 270 overlies flap 266 and the tabs 274 and 276 are respectively tucked into the cutouts 280 and 278 of the flap 266.

Lateral elements along the other edge of the blank serve to form a bottom closure for the box and also form additional partitions for completing the division of the box into twelve compartments. Elements 282 and 284, foldable on score lines 281 and 283 are associated with the panel 260. Folding on these lines brings the element

284 into parallelism with the partition panel 262 forming a second partition which runs down the center of the box. Slits 285 and 286, running across the elements 262, 282 and 284 are provided for accommodating and cooperating with transverse partition elements 288 and 290. These elements are connected to end panels 256 and 252 by intermediate elements 292 and 294 being foldable on score lines 289-293 and 291-295 to place the intermediate elements 292 and 294 at right angles to the end panels 256 and 252 and the partition elements 288 and 290 into parallelism with them. The notches or slots 296 and 297 fit together with the slits 285 and 286.

15 A third longitudinal partition 298 completes the internal structure. This partition is connected to the panel 258 by an intermediate element 300, folds occurring on the score lines 299 and 301. When folded, the element 300 is at right angles to the wall 258, forming part of the bottom closure and partition 298 is parallel to this wall, forming the third longitudinal partition for completing the division of the box into twelve compartments. Notches or slits 302 cooperate with the slits 304 in the transverse partitions 288 and 290.

20 The bottom closure is completed by the element 306 which folds on score line 307 over the element 300 and is secured in place by tabs 308 and 309 which tuck into the cutouts 310 and 311 of the element 300.

25 The forming and filling of the container comprises first the formation of the collapsed container of Figure 19 as above described, and the container will normally be shipped to the customer in this condition. The setting up of the container involves first opening out the collapsed container by pressing against its opposite edges. Next the partition wall 284 is folded up into place and the transverse partitions 288 and 290 are wiped into place, the parts being self-positioning as in the case of the elements 38 and 44 of Figure 1. The third longitudinal partition is now folded in, being also self-positioning by means 30 of the notches 302 and slits 304, and the bottom closure is completed by folding over the elements 300 and 306 and tucking in the tabs 308 and 309. The box now presents the appearance of Figures 20 to 23 and may be loaded with twelve bottles or other articles. Folding over the top elements 268, 272, 266 and 270 and securing them by tucking in the tabs 274 and 276 completes the closure.

35 The dimensional relationships of the elements of the blank of Figure 18 will be generally evident from the foregoing description of the manner in which they fit together. Apart from fold allowance, end walls 252 and 256 are of equal width, and the side walls 254 and 258 and the partition 262 are of equal width, element 260 which positions the partition 262 is substantially one quarter of the width of the end walls 252 and 256 and the element 264 may be narrower since it is positioned accurately by the folding of other parts and is held by adhesive. The remaining and transversely foldable elements conform to the dimensions of the box as defined by the longitudinally folded parts. The formation of longitudinal partitions by transversely folded elements as well as longitudinally folded elements permits the use of a plurality of longitudinal partitions, thus increasing the number of different arrangements of compartments which may be provided by comparison with the blank of Figures 1 to 6.

40 45 50 55 60 65 70 75

Fourth modification

A partitioned box with the partition supported by elements extending in opposite directions so as to form a Z configuration, instead of a U configuration such as is produced by the parts 2, 4 and 6 of Figures 1 to 6, may be produced and such a box is illustrated in Figures 24 to 28.

The blank shown in Figure 24 comprises a series of panels 320, 322, 324, 326, 328, 330, 332 and 334 separated by score lines 321, 323, 325, 327, 329, 331 and 333 and a cut 335 midway of the score line 331. The first fold occurs on the line 329, bringing panel 330 face to face with panels 328 and 326 and bringing panels 332 and 334 face to face with panel 326. Panel 334 will previously be prepared with adhesive over the area C thus joining panel 334 to panel 326. The next fold occurs on line 325 bringing the reverse of panels 330, 332 and 334 over the face of panels 322 and 324. The last fold occurs on line 321 bringing the face of panel 320 over the reverse of panel 328 which will previously have been prepared with adhesive B on its reverse as indicated in phantom, thus joining these elements together to complete the collapsed box as shown in Figure 25.

When the collapsed box of Figure 25 is opened out by pressing against its opposite edges, the parts assume the position of Figure 28, the element 332 forming a partition which, in the embodiment shown, divides the box into two equal compartments. Cutout 335 forms a tongue 336 continuing the panel 330 and lying along the side wall 322 to prevent a flat article, such as an adhesive bandage, from slipping in back of panel 330. Flaps of conventional type may be provided as indicated for closing the ends of the box and the partition forming elements 330, 332 and 334 may be of less height than the wall elements 322, 324, 326 and 328, thus providing space for the tuck-in tabs 337 of the end closures.

Fifth modification

The principles of the invention may also be applied for producing a spacer for a carton which holds an article or container of stepped cross sectional form, thus giving the carton an L-shaped internal form. Such a container is illustrated in Figures 29 to 33, inclusive.

The blank as shown in Figure 29 comprises an aligned series of panels adapted for continuous folding in one direction as before, the panels 340, 342, 344, 346, 348, 350, 352 and 354 being separated by folding score lines 341, 343, 345, 347, 349, 351 and 353. The first fold occurs on score line 345, bringing end panel or flap 340 over the panel 348 and joining it thereto by means of previously applied adhesive B.

The next fold occurs on line 349, bringing the reverse of panels 340, 342 and 344 and part of the face of panel 348 over panels 350 and 352. The last fold occurs on line 353 bringing the face of panel 354 over the face of panel 352 and reverse of panel 346 and joining it to the latter by means of adhesive C. The collapsed container now presents the appearance of Figure 30 and may be set up by opening the collapsed container by pressing against its opposite edges. When so opened up the parts present the appearance of Figure 31, one corner being walled off by the elements 342 and 344 so that the remainder of the box is of L-shaped configuration.

Comparison of Figure 31 with Figure 3, so far as the longitudinally folded elements are con-

cerned, shows that the element 344 occupies a position similar to element 4. Reduction of its width, however, brings element 342 (corresponding generally to element 2) away from wall 350 and toward wall 354, and the additional flap 340 is provided for joining element 342 to the wall 348. The second panel 344 (neglecting the glued flap 340) being of less width than the fourth panel 348 spaces the first panel 342 from the fifth panel 350. Similarly, the first and third panels 342 and 346 being of less width than the fifth panel 350, provide for the spacing of panel 344 from panel 352. By varying the dimensions of these elements, a box within the interior of the container and forming a spacer block of any desired dimension may be formed.

Closure of the box is completed by upper and lower flaps as indicated and the upper tuck-in flap 355 is accommodated by terminating flap 340 below the upper edge of the box, as shown. The lower borders of panels 342 and 344 may be cut diagonally, as shown.

What I claim is:

1. A container comprising a series of connected panels folded continuously in one direction and including panels forming exterior walls and a panel forming a partition connecting two opposite walls so as to divide the container into two compartments and comprising also transversely folded panels connected to the said partition forming panel and forming a second partition parallel thereto, transversely folded partition-forming panels connected to a wall parallel to the said partitions and forming still a third partition parallel to the first said partitions, and a transversely folded panel element connected to one of the said opposite walls of the container and forming a cross partition whereby the container is divided into sub-compartments.

2. A container comprising a series of connected panels folded continuously in one direction and including panels forming exterior walls and a panel forming a partition connecting two opposite walls so as to divide the container into two compartments and comprising also transversely folded panels connected to the said partition forming panel and forming a second partition parallel thereto, transversely folded partition-forming panels connected to a wall parallel to the said partitions and forming still a third partition parallel to the first said partitions, and transversely folded panel elements connected to the said opposite walls of the container and forming cross partitions whereby the container is divided into sub-compartments.

3. A container comprising a series of connected panels folded continuously in one direction and including panels forming exterior walls and a panel forming a partition connecting two opposite walls so as to divide the container into two compartments and comprising also transversely folded panels connected to the said partition forming panel and forming a second partition parallel thereto, and transversely folded panel elements connected to one of the said opposite walls of the container and forming a cross partition whereby the container is divided into sub-compartments.

4. A container according to claim 3, comprising transversely folded panel elements connected to each of the said opposite walls and forming two cross partitions.

5. A container comprising a series of connected panels folded continuously in one direction and including panels forming exterior walls and a

panel forming a partition connecting two opposite walls so as to divide the container into two compartments and comprising also transversely folded partition forming panels connected to a wall parallel to the said partition and forming a partition parallel to the first said partition, and transversely folded panel elements connected to one of the said opposite walls of the container and forming a cross partition whereby the container is divided into sub-compartments. 10

6. A container according to claim 5, comprising transversely folded panel elements connected to both of the said opposite walls and forming two cross partitions.
